DESIGN FOR A BAKING UNIT

John F. Cavanagh, Providence, R. I.

Application May 1, 1947, Serial No. 138,741

Term of patent 14 years

(Cl. D81—10)

To all whom it may concern:

Be it known that I, John F. Cavanagh, a citizen of the United States, residing at Providence, in the county of Providence and State of Rhode Island, have invented a new, original, and ornamental Design for Baking Unit, of which the following is a specification, reference being had to the accompanying drawing, forming part thereof.

Figures 1 and 2 are perspective views of a baking unit, showing my new design as seen substantially from the front and rear respectively, the unit being closed.

I claim:

The ornamental design for a baking unit, substantially as shown.

JOHN F. CAVANAGH.
